UNITED STATES PATENT OFFICE.

BENJAMIN B. DUDLEY, OF VISALIA, AND EDWARD R. DUDLEY, OF PIEDMONT, CALIFORNIA.

COLLAPSING OIL DRILL.

Application filed August 24, 1925. Serial No. 52,238.

This invention relates to well drilling bits in general, but in particular to bits of the reciprocating type adapted for drilling a hole larger than the casing through which the bit works.

The principal objects of the invention are to provide a drill bit of this kind, of extreme simplicity and ruggedness, and which with its associated parts will drill a straight hole and effectively flush the hole with a hydraulic jet through the drill point while drilling, and which combination will provide for drilling a relatively great increase in depth of hole at each setting of the casing.

The above and other objects are attained through the construction shown in the accompanying drawings and in which:—

Figure 1 is a sectional elevation of the lower end of a well with our drill in expanded drilling position below the end of the casing;

Figure 2 is a transverse section along the line 2—2 of Figure 1;

Figure 3 is an end view of the cutting edges of the drill expanded;

Figure 4 is an elevation of the drill detached from its surrounding structure;

Figure 5 is a sectional elevation of the lower end of the well showing the drill collapsed and being drawn within the casing;

Figure 6 is an enlarged view of one of the collapsing jaws of the drill;

Figure 7 is a side view of Figure 6;

Figure 8 is a perspective view of the jaw retaining block;

Figure 9 is a cross-sectional view of Figure 1 along the line 9—9 thereof;

Figure 10 is a perspective sketch of the special packing ring used.

Briefly described, our invention comprises a drill with slideable collapsing jaws which automatically collapse by striking against the lower end of the well casing in pulling the drill, and of the mounting of the drill on a long guiding tube working within the casing so that the drill when expanded will upon reciprocation drill a larger hole than the casing and at all times concentric therewith even to a distance, in practice, some forty feet or more beyond the lower end of the casing so that the casing only has to be lowered after about every forty feet of drilling, also this combination with the hydraulic jet feature alluded to so that the material cut loose by the drill will

be constantly forced to the top of the well between the outside of the casing and the drilled hole which is larger than the casing.

In the illustrations, our drill comprises a shank 1 having a fixed jaw 2 of a maximum diameter to pass through a well casing 3.

This jaw 2 is beveled at its cutting edge as shown at 2', and at right angles is arranged a pair of collapsible jaws 4 also with beveled cutting edges as shown at 4'.

The collapsing jaws 4 each have a shank 5 slidably supported in a recess 6 in the main shank 1 of the drill so that they are free to slide longitudinally of the drill body 70 and they are retained in position by passing under an enlarged portion or hub 7.

The hub diameter is equal to the width of fixed jaw 2 and at the upper part the hub is beveled at 7' where it joins the shank so as to be guided into the casing in pulling the drill, and a retaining block 8 is provided on each sliding jaw shank so that the jaws cannot be slid entirely off of the drill body.

This block 8 is shown clearly in Figure 8 and is seen to be provided with a dovetail slot 9 which fits over a complementarily shaped jaw 10 formed on the jaw shank, so that the block 8 is slid transversely into engagement with the shank of the jaw to the position shown in Figures 1 and 4, after which it is secured in place by a screw 11 passing through the block and entering a recess 12 in the shank.

When the jaws are pulled out to their maximum extension the jaws collapse and the blocks 8 abut against a shoulder 13 on the hub formed by notching opposite sides thereof, and the blocks are provided with teeth 14 so that they will cut out any mud or stone from the shoulder when seating.

When the jaws are pushed all the way into their respective recesses, the jaws expand and a heavy square shoulder 15 engages a shoulder 16 on the drill hub so as to take the force of drilling, the sliding jaws having wings 33 bearing against the vertical walls 34 of the fixed jaw.

The expanding and collapsing of the jaws through longitudinal sliding is accomplished by cooperatively tapering the jaw shanks as shown at 17 and the central portion of the fixed jaw 2 as indicated at 18.

Thus when the jaws are slid all the way up they are firmly seated against the shoul-

ders as described and expanded to the position shown in Figures 1, 3 and 4 and held from falling by the friction of flat springs 19 secured within the recesses 6 and over 5 which the shanks of the jaws slide while being forced outwardly thereby.

When expanded as shown, in pulling the drill, the jaws will strike the lower end of the casing shoe 20 and casing 3 which will 10 slide them down along the body to position shown in Figure 5 seating the inner surface of the shanks against the wedge like sides 18 of the central portion of the fixed jaw 2, thus bringing the sliding jaws together as 15 shown to thereby clear the inside of the casing for withdrawal from the well.

When expanded the drill upon reciprocation will drill a hole 21 larger than the casing 3 or its shoe 20, and a hole 22 extending 20 through the shank of the drill and emerging at points 22' provides for forcing water directly between the cutting edges of the drill in operation.

The drill is screwed at 23 to a tubular 25 operating shank 24 consisting of several sections of tubing coupled as at 25 to provide preferably a length of some forty feet, and at the upper end the tubing is closed by a head 26 provided with ports 27 for forcing 30 water to the drill from within the casing 3.

The lower portion of this casing 3 is preferably of a heavier gage than the casing 35 above it extending to the surface of the well for suspension in the known manner, and this heavier gage portion is preferably about sixty feet in length to function as a long working barrel in drilling to guide the head 26 of the reciprocating drill vertically yet provide for a relatively long extension of 40 the hole each time before making it necessary to lower the casing.

At the upper end of the tubular shank 24 and surrounding the head 26 is a long packing ring 28 sealing off the casing from this 45 point down so that water forced down in the casing above this ring will have to pass through the openings 27 to the interior of the hollow shank 24, and thence to emerge from the passages 22' to the cutting edges 50 of the drill. This results in a powerful jet at the cutting edges washing away all loosened material and forcing it upwardly through the annular space 29 outside of the casing to the top of the well 1, since no other channel for its discharge exists.

The ring 28 is a split ring and of about three inches in depth so it will ride over the casing joints in withdrawing the drill and

it is prevented from catching on the joints through its special construction.

It is really two split rings 28 and 28' secured together at some point or points and each section has overlapping ends as indicated in Figure 10 where the ends A and B are separated so as to better indicate its 65 structure.

The inner section extends below the outer section and seats in a groove 35 in the head 27 which permits though limits its outward expansion and it is held longitudinally in 70 place by a pair of threaded collars 30—31' locked together above it on the head with just sufficient clearance above the ring for it to operate.

Thus the ring is forced to follow the vertical motion of the drill in operation yet is free for limited expansion, so that when the drill is pulled from the reduced internal diameter working barrel portion of the casing 3 to the slightly larger string above it, the 39 ring will freely pass all the casing joints on the way out, or when lowering the drill to place after sharpening the same.

To better clear the joints the upper and lower corners of the outer ring section 28 are 85 well rounded as shown.

Above the head 26 is a suitable coupling socket 32 for attaching the ordinary drilling cable, not shown.

We claim:

1. A well drill comprising a body with jaws slideable longitudinally thereon from a collapsed to an expanded position, and shoulders on said body and jaws adapted to engage one another when the jaws are expanded, and a lug on each of said jaws engaging a portion of the body when the jaws are collapsed, said lug and portion presenting spaced points of contact.

2. A collapsing well drill comprising a 100 drill shank with longitudinal grooves thereon, jaws with shanks each slidably positioned in one of the grooves whereby the jaws are slideable lengthwise of the drill shank, means for retaining the jaws in place 105 while permitting sliding action, and means for frictionally retaining the jaw shanks in position in the grooves.

3. A reciprocable well drill, cutting jaws on said drill adapted to slide from a collapsed position to an expanded position upon end impact against the drill in operation, and means for frictionally holding the jaws in expanded relation to the drill.

BENJAMIN B. DUDLEY.
